JOHN LEONARD HOLMAN AND ARTHUR TREVE HOLMAN, OF CAMBORNE, ENGLAND,
ASSIGNORS TO HOLMAN BROTHERS LIMITED, OF CAMBORNE, ENGLAND, A BRITISH
COMPANY.

VALVE MECHANISM FOR FLUID-OPERATED ROCK DRILLS.

Application filed January 20, 1927, Serial No. 162,313, and in Great Britain October 14, 1926.

This invention consists in improvements in or relating to valve mechanism for fluid-operated rock drills and like tools. The invention relates to that kind of tool in which 5 there is a cylinder, a reciprocating piston therein, inlet ports for the driving fluid leading respectively to opposite ends of the cylinder and a valve for controlling the admission of driving fluid alternately to the 10 ports aforesaid.

The type of valve to which the invention relates is a flap valve which may conveniently be hinged at or near one end and operates by oscillatory movement about its hinge to 15 control by its opposite faces respectively the two inlet ports which lead to the opposite ends of the working cylinder. In this type of valve oscillatory movement is brought about by variations in the pressure acting on 20 the opposite faces of the valve.

The principal object of this invention is to provide means whereby the movement of the flap valve from one position to the other is effected more rapidly and with greater 25 certainty than in constructions hitherto proposed.

According to the present invention in a fluid-operated rock drill or like tool of the kind described having valve mechanism of 30 the type specified in which a flap valve has one face closed against an inlet port by the pressure on its opposite face of the driving fluid entering the valve chamber, there is provided means to admit pressure fluid to 35 the aforesaid face of the valve which is closed against its corresponding inlet port so as to balance or partially balance the pressure of the driving fluid acting to hold the valve closed. When the pressure of the 40 driving fluid is reduced by the exhaust to below that of said pressure fluid, the latter will act to move the valve to close the other of the two inlet passages.

A feature of the invention consists in a 45 valve having means to admit pressure fluid, as above described, to the face of the valve which is closed against its corresponding inlet port and which is arranged so that the length of the valve transverse to the axis 50 about which it oscillates is parallel with the

throughway axis of the cylinder the fluid-admission to which is controlled by the valve.

Conveniently, the aforesaid means to admit pressure fluid to the closing face of the 55 valve is constituted by a throughway aperture or apertures leading from one face of the valve to the other.

Preferably, one face of the valve seats on to the outer wall of the cylinder or on to a 60 liner surrounding said outer wall, and said valve face is recessed to form a cavity with which the aforesaid throughway apertures in the valve communicate.

In order that the invention may be more 65 clearly understood one form thereof will now be described by way of example only with the aid of the accompanying drawings in which:—

Figure 1 is a sectional elevation through 70 a cylinder and valve of a rock drill, the section being taken in a plane containing the axis of the cylinder; and

Figure 2 is a plan of the valve.

Only so much of a rock drill as is necessary to the understanding of the invention has been illustrated. As is usual, there is provided a main cylinder 10 in which is a hammer-piston 11 associated in known manner with a twist-bar 12 and the usual ratchet 80 twist mechanism. In the wall of the cylinder is a free exhaust port 13, the opening and closing of which is controlled by movement of the piston 11.

Within a valve chamber 14 there is a main 85 air-inlet valve 15 which is in the form of a plate-valve hinged at one end 16, by means of a transverse rib which is received within a correspondingly shaped groove in a transverse inner portion of the valve-chamber. 90 Compressed air enters the chamber 14 through a main inlet 17 opening into one end of the valve-chamber in the region of the free end of the valve 15. A transverse bridge 18 serves as one seat for the valve 15 95 and air is enabled to pass between the adjacent faces of the bridge and the valve to a main air-inlet port 19 when the valve is in the lower position illustrated. The port 19 leads to the left-hand end of the cylinder 10, 100

and another inlet port 20 for the right-hand end of the cylinder is controlled by the lower face of the valve 15.

The valve 15 has a recess 40 formed in its lower face which seats onto the cylinder 10 and apertures 41 through the valve afford communication between the air-inlet 17 and the said recess.

In operation compressed air enters the main inlet 17, and, in the position of the valve illustrated, passes over the valve 15 through the port 19 to the left-hand end of the cylinder, and also through the apertures 41 into the cavity formed by the recess 40 and the outer wall of the cylinder 10. The cavity 40 presents a surface of such dimensions to the pressure of the driving fluid admitted through the apertures 41 that the total pressure of the air in this cavity balances or partially balances the pressure of the air on the upper surface of the valve 15. As the piston travels to the right it opens the exhaust port 13, whereupon the pressure is immediately reduced in the left-hand end of the cylinder and above the valve 15. Consequently, the valve is then very rapidly raised, thereby closing the passage 19 by engagement of the upper surface of the valve 15 with the bridge 18, due mainly to the pressure of the fluid in the cavity aforesaid. This movement of the valve is assisted by the compression produced in the right-hand end of the cylinder which acts on the under surface of the valve 15 through the port 20. The compressed air then flows from the inlet 17 through the port 20 to the right-hand face of the piston. As the piston travels to the left it opens the exhaust port 13 whereupon the pressure is reduced in the right-hand end of the cylinder and under the valve 15. The pressure on the portion of the valve projecting beyond the bridge 18 into the inlet 17 and the compression from the front end of the cylinder on the part of the valve in the passage 19 immediately closes the valve and the cycle of operations is reversed, and subsequently repeated.

The construction described above in detail is given as one example only of the invention, and it is to be understood that the design of the parts may be modified without departing from the scope of the invention as defined by the appended claims. The invention may be applied to any valve mechanism of the type described, for example to any of the constructions described and illustrated in the specification of British application for Letters Patent No. 6307 of 1926.

We claim:-

1. For a fluid-operated rock-drill, the combination of a valve-chamber having two outlet-ports leading therefrom, a swinging flap-valve which is hinged at one end in said chamber and which has two valve-faces for controlling respectively the two outlet-ports

and means which, when one valve-face is held against one of said ports by pressure of driving-fluid on its opposite face, will admit driving-fluid also to that valve-face which is held against the outlet-port but not that portion that covers the port, so as at least partially to balance the pressure of the driving fluid acting on its other face to hold the valve closed. 70

2. For a fluid-operated rock-drill, the combination of a valve-chamber having two outlet-ports leading therefrom, a swinging flap-valve which is hinged at one end in said chamber and which has two valve-faces for controlling respectively the two outlet-ports 75 and at least one throughway passage in the valve which, when one valve-face is held against one of said ports by pressure of driving-fluid on its opposite face, will admit driving-fluid also to that valve-face which is held against the outlet-port but not that portion that covers the port so as at least partially to balance the pressure of the driving fluid acting on its other face to hold the valve closed. 80

3. For a fluid-operated rock-drill, the combination of a drill-cylinder, a valve-chamber situated in the side of the drill-cylinder and having two outlet-ports leading therefrom, a swinging flap-valve which is hinged at one 85 end in said chamber and which has two valve-faces for controlling respectively the two outlet-ports and means which, when one valve-face is held against one of said ports by pressure of driving-fluid on its opposite face, will admit driving-fluid also to that valve-face which is held against the outlet-port but not that portion that covers the port so as at least partially to balance the pressure of the driving fluid acting on its other face to hold the valve closed. 90

4. For a fluid-operated rock-drill the combination of a valve-chamber having two outlet-ports leading therefrom, a swinging flap-valve which is hinged at one end in said 100 chamber and which has two valve-faces on opposite sides of the valve for controlling respectively the two outlet-ports and means which, when one valve-face is held against the appropriate outlet-port by pressure of 105 the driving-fluid on the opposite side of the valve, will admit driving-fluid between the side of the valve having that valve-face and an adjacent wall of the valve-chamber so as at least partially to balance the pressure of 110 the driving-fluid acting on the said opposite side of the valve. 115

5. For a fluid-operated rock-drill the combination of a valve-chamber having two outlet-ports leading therefrom, a swinging flap-valve which is hinged at one end in said 120 chamber and which has two valve-faces on opposite sides of the valve for controlling respectively the two outlet-ports, a recess in one side of the valve, and means which, when 125

the valve-face on that side of the valve is held against the appropriate outlet-port by pressure of the driving-fluid on the opposite side of the valve, will admit driving-fluid to said recess so as at least partially to balance the pressure of the driving-fluid acting on the said opposite side of the valve.

6. For a fluid-operated rock-drill the combination of a valve-chamber having two outlet-ports leading therefrom, a swinging flap-valve which is hinged at one end in said chamber and which has two valve-faces on opposite sides of the valve for controlling respectively the two outlet-ports and at least one throughway aperture in the valve, which, when one valve-face is held against the appropriate outlet-port by pressure of the driving-fluid on the opposite side of the valve, will admit driving-fluid between the side of the valve having that valve-face and adjacent wall of the valve-chamber so as at least partially to balance the pressure of the driving-fluid acting on the said opposite side of the valve.

7. For a fluid-operated rock-drill, the combination of a valve-chamber having two outlet-ports leading therefrom, a swinging flap-valve which is hinged at one end in said chamber and which has two valve-faces on opposite sides of the valve for controlling respectively the two outlet-ports, a recess in one side of the valve, and at least one throughway aperture in the valve which when the valve-face on that side of the valve is held against the appropriate outlet-port by pressure of the driving-fluid on the opposite side of the valve, will admit driving-fluid to said recess so as at least partially to balance the pressure of the driving-fluid acting on the said opposite side of the valve.

8. For a fluid-operated rock-drill the

combination of a drill-cylinder, a valve-chamber situated on the side of the drill-cylinder and having two outlet-ports leading therefrom, a swinging flap-valve which is hinged at one end in said chamber and which has two valve-faces on opposite sides of the valve for controlling respectively, the two outlet-ports, a recess in one side of the valve, and at least one throughway aperture in the valve which when the valve-face on that side of the valve is held against the appropriate outlet-port by pressure of the driving-fluid on the opposite side of the valve, will admit driving-fluid to said recess so as at least partially to balance the pressure of the driving-fluid acting on the said opposite side of the valve.

9. For a fluid-operated rock-drill, the combination of a cylinder having a valve-chamber, a short direct outlet-passage leading from the valve-chamber to one end of the cylinder, a bridge situated between two ends of the chamber and affording a relatively long passage to the other end of the cylinder, a swinging flap-valve hinged at one end in said chamber having on opposite sides of the valve two valve-faces for closing respectively said short direct passage and said relatively long passage, the said long passage comprising a substantial portion of the appropriate face of the valve, and at least one throughway aperture in the valve for admitting driving-fluid to that side of the valve having the valve-face which closes said short direct passage to the cylinder but not to the said valve-face.

In testimony whereof we have signed our names to this specification.

JOHN LEONARD HOLMAN.
ARTHUR TREVE HOLMAN.
